CLAIM

The ornamental design for a storage device for optical media such as CDs or DVDs, as shown and described.

DESCRIPTION

FIG. 1 is a perspective view of a storage device for optical media such as CDs or DVDs, showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken line showing of the latch, side loops, and hinges is included for the purpose of illustrating environment and forms no part of the claimed design.

1 Claim, 5 Drawing Sheets
